UNITED STATES PATENT OFFICE.

WILLIAM G. MONTGOMERY, OF ERIE, PENNSYLVANIA, ASSIGNOR OF ONE-HALF TO GEORGE W. REED, OF ERIE, PENNSYLVANIA.

STOVE-DAMPER.

SPECIFICATION forming part of Letters Patent No. 727,178, dated May 5, 1903.

Application filed January 17, 1903. Serial No. 139,462. (No model.)

To all whom it may concern:

Be it known that I, WILLIAM G. MONTGOMERY, a citizen of the United States, residing at Erie, in the county of Erie and State of Pennsylvania, have invented certain new and useful Improvements in Stove-Dampers; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to improvements in stove-dampers; and it consists substantially in the construction of a damper with a detachable spindle adapted to be attached or detached from the damper-plate by means of 20 a longitudinal movement of the spindle.

Another feature of my improved stove-damper is that the plate and spindle are so made that the spindle can be inserted into either end of the slot with equal facility, a 25 spring on the shank of the spindle operating against the exterior of the pipe to retain the spindle in engagement with the damper-plate.

The features of my invention are herein- 30 after fully set forth and described, and illustrated in the accompanying drawings, in which—

Figure 1 is a view in elevation of a stove-damper embodying my invention. Fig. 2 is 35 a view in elevation of the damper-plate without the spindle. Fig. 3 is a view in elevation of the spindle. Fig. 4 is a section of my improved stove-damper on the line $x-x$ in Fig. 1. Fig. 5 shows a transverse section of pipe 40 with the spindle and damper-plate in position to be placed in engagement with each other.

In the drawings, A is a damper-plate having a transverse semicircular central slot or 45 depression A' therein and provided with a draft-opening a and rectangular openings a' at each side thereof through the slot or depression A' and semicircular extensions a'' of said openings a' at the sides thereof, 50 as clearly illustrated in Figs. 1 and 2.

B is a cylindrical spindle provided at one end with a thumb-piece C and a collar c, against which a retracting-spring D operates.

On opposite sides of the spindle B, I make lugs or projections b , adapted to pass through the extensions a'' at the sides of the openings a' when the spring D is compressed and be drawn back under the plate A at the ends of the openings a' therein when the spring expands to retain the spindle in place in the slot A', as illustrated by full and dotted lines in Fig. 1, and which lugs b also operate on the plate A to compel it to rotate with the spindle B.

In connecting the plate A with the spindle B the spindle is inserted through a pipe E. (See Fig. 5.) The plate A is then moved toward it, as illustrated in Fig. 5. The spring D is then compressed, which moves the spindle B longitudinally until the lugs b on the spindle will pass through the extensions a'' of the openings a' , when, the plate A being moved toward the spindle, the spindle enters the semicircular slot A' in the plate A, after which the spring D is allowed to expand and move the lugs b back under the plate, as illustrated in Fig. 4, and thus firmly lock the spindle to the plate.

Having thus described my invention, so as to enable others to construct and use the same, what I claim as new, and desire to secure by Letters Patent of the United States, is—

1. The combination in a stove-damper, of a damper-plate having a semicircular transverse slot and openings therethrough, a spindle, lugs on the spindle adapted to pass through the openings in the plate, and a retracting-spring on the shank of the spindle, substantially as and for the purpose set forth. 85

2. The combination in a stove-damper, of a damper-plate having a central transverse slot or depression therein, with openings therethrough and extension-openings at the sides thereof, a round spindle having two 90 lugs thereon at opposite sides thereof adapted to pass through the extensions in the openings in the plate, and a retracting-spring on the shank of the spindle, substantially as and for the purpose set forth. 95

In testimony whereof I affix my signature in presence of two witnesses.

WILLIAM G. MONTGOMERY.
